UNITED STATES PATENT OFFICE.

MARCY L. WHITFIELD, OF MEMPHIS, TENNESSEE, ASSIGNOR TO THE
WHITFIELD COMPANY, OF SAME PLACE.

SEMICOMPPOUND TELESCOPIC ENGINE.

SPECIFICATION forming part of Letters Patent No. 678,709, dated July 16, 1901.

Application filed December 9, 1899. Serial No. 739,833. (No model.)

To all whom it may concern:

Be it known that I, MARCY L. WHITFIELD, a citizen of the United States of America, residing at Memphis, in the county of Shelby 5 and State of Tennessee, have invented certain new and useful Improvements in Semi-compound Telescopic Engines; and I do hereby declare the following to be a full, clear, and exact description of the invention, such as 10 will enable others skilled in the art to which it appertains to make and use the same, reference being had to the accompanying drawings, and to letters and figures of reference marked thereon, which form a part of this 15 specification.

This invention has relation to steam or other motive fluid engines and more especially to high-pressure double-acting steam-engines; and it has for its object a construction of engine which can be operated more economically, is more compact, and can be built at a less cost than similar engines of like power as heretofore constructed. These objects I attain, first, by combining with the power-cylinder a differential piston and means for automatically causing boiler-steam to act alternately on opposite faces of said piston; second, by combining with the power-cylinder a differential piston, means for automatically causing boiler-steam to act alternately on opposite faces of said piston, and means for automatically causing the steam acting on the smaller piston area to also act, together with boiler-steam, on the larger piston area, the engine working what I term "semicom-pound," in that when the steam acting on the smaller piston area is caused to act, together with boiler-steam, on the larger piston area such steam acts more or less expansively, as will be readily understood, the engine working therefore as a semicom pound high-pressure double-acting engine; thirdly, by combining a stationary cylinder, a cylinder working therein and hereinafter referred to as the "piston-cylinder," the inner head of which constitutes the piston for said stationary cylinder, and thus providing differential piston areas, and a stationary abutment on which said piston-cylinder reciprocates, the head of said abutment constituting the outer head of said piston-cylinder, with means for admit-

ting boiler-steam to the piston-cylinder to effect the instroke, means for exhausting the steam from said piston-cylinder into the stationary cylinder at or about the completion of such instroke and for, simultaneously admitting boiler-steam to said stationary cylinder for effecting the outstroke; fourthly, by using a bifurcated abutment, serving not only as a steam-supply duct, but providing a way between its legs, in which the cross-head connected to the piston-cylinder and crank-shaft can reciprocate, whereby the length of the engine is materially shortened; fifthly, by connecting the steam-duct in one of the legs of the abutment directly with the education-port in the valve-chest for the distributing or expansion valves and by admitting boiler-steam through said abutment to and through the piston-cylinder to the stationary cylinder, whereby a complex arrangement of steam ducts and pipes, which would be otherwise necessary, is avoided; sixthly, by providing in the head of the piston-cylinder a cylindrical valve, hereinafter referred to as the "intermediate" valve, timed to open when said piston-cylinder is about to complete or has completed its instroke, causing the steam therein to exhaust and expand into the stationary cylinder, together with the boiler-steam admitted simultaneously through the bifurcated abutment and piston-cylinder, and, lastly, by carrying the rod connected with the intermediate valve in the head of the piston-cylinder in the direction of the crank-shaft, instead of carrying said rod in an opposite direction through the head of the stationary cylinder, with a view to a further reduction in the length of the engine.

That my invention may be fully understood, 90 I will describe the same in detail, reference being had to the accompanying drawings, in which—

Figures 1 and 2 are opposite side elevations, the fly-wheel being removed in Fig. 1 and partly broken away in Fig. 2, in which latter figure the distributing or expansion valves and steam-passage controlled thereby, as well as the steam-passage in one of the legs of the bifurcated abutment, are shown in dotted lines. Fig. 3 is a top plan view, and Figs. 4 and 5 vertical and horizontal longitudinal

sections, of an engine embodying my invention, the fly-wheels in both the latter figures being partly broken away and the distributing or expansion valves and the steam-passages controlled thereby, as well as the steam-passage in one of the legs of the bifurcated abutment, being shown in dotted lines in said Fig. 4. Fig. 6 is a detail top view of the bifurcated abutment. Fig. 7 is a vertical longitudinal section of the distributing valve-chest and valves, a portion of the leg of the stationary abutment broken away to show the steam-passages therein in their relative positions shown in Fig. 1. Fig. 8 is a section of Fig. 7, taken on line xx looking in the direction of arrow $7x$, and Fig. 9 is a horizontal section taken on line yy of Fig. 7, said Figs. 7 to 9 being drawn to an enlarged scale.

The engine is attached to a suitable framing a , provided with bearings for the power or crank shaft b , which carries, as usual, a fly-wheel w , and to said framing is secured the bifurcated abutment f , the head 2 of which is constructed piston-like and fits fluid-tight into the piston-cylinder d . As clearly shown in Figs. 4, 5, and 6, the legs 3 of said abutment extend directly from its piston-head 2 , so as to form a guideway for the reception of the cross-head connected with the piston-cylinder and hereinafter referred to, and in leg 3 of said abutment is formed a steam-passage 5 , which is connected to the inlet-port 6 , Figs. 6, 7, and 8, through the main or distributing valve-chest k , secured directly to said leg or preferably cast therewith, said steam-passage leading into the piston-cylinder d through a port 7 in the head of the abutment, which latter is braced on one side of the engine-frame by means of a brace-rod h , Figs. 2, 3, and 5.

To the engine-frame y is bolted the large cylinder c , in which works the piston-head 8 of the piston-cylinder d , and in said head is formed a valve-chamber for the semirotary or oscillating cylindrical intermediate valve 9 , which has suitable ports or passages 10 , Fig. 4, adapted to register with ports or passages 11 , leading from said valve-chamber into said piston-cylinder d . On the outer head 31 of the large cylinder c is bolted a valve-casing 32 for an oscillating or semirotary cylindrical exhaust-valve e , provided with suitable ports or passages, adapted to place the exhaust-pipe g and cylinder c in communication.

The intermediate valve 9 has secured to its stem a radial arm terminating in a toothed sector 12 in gear with a like sector 13 on the actuating-rod i , oscillating in suitable bearings and feathered to a toothed sector or cam l , gearing with a toothed portion of a rocker m , rocked by a rod n through the main valve-lever o of a well-known valve-gear, said main lever o being operated by the rod p of an eccentric q on the crank-shaft b , while the exhaust-valve e receives its movements through a radial arm 14 , adjustably connected to an

actuating-rod 15 , operated by the aforesaid rocker m . (See Figs. 1, 3, and 5.)

In Fig. 1, s and t indicate the main valves, connected, as usual, with pistons of dash-pots u v , said valves s t being under the control of a governor x through well-known connections, said governor being belted in a well-known manner to the crank-shaft b , Fig. 1. These valves are arranged in a valve-chest k , to which the boiler-steam-supply pipe k' is bolted.

The piston-cylinder d has formed thereon guide-blocks 16 , reciprocating on and being guided by guides x , which, with the intermediate portions y , to which said guides are secured, constitute the intermediate portion of the engine-frame a , and to said guide-blocks 16 is connected the cross-head z , reciprocating, as hereinabove stated, between the legs 3 and 4 of the stationary abutment f , said cross-head z being connected by the driving-rod r with the crank 17 of the crank-shaft b .

In order to avoid the formation of a partial vacuum in the stationary cylinder c , which may happen when the engine is working under a very light load and the cut-off very early by the steam expanding below atmospheric pressure, involving, as is well known, a great loss, I provide an automatic relief-valve 18 , Fig. 4, suitably held by a spring 19 and seating in a passage 20 in the cylinder-head 31 , so as to open inwardly against the stress of said spring, as more clearly shown in Fig. 4.

By using a bifurcated stationary abutment f , the legs of which extend directly from its piston-head 2 to form a way for the cross-head z , I am enabled to reduce the length of the engine to a minimum, as it is obvious that the cross-head can work closer to the stationary cylinder than is the case in ordinary engines in which the travel is limited by a stuffing-box.

The operation of the various valves is so timed that when one of the distributing or expansion valves s or t is open the other is closed, that when valve t is open the intermediate valve 9 is closed and the exhaust-valve e is open, and that when valve s is open the intermediate valve 9 is also open and the exhaust-valve e is closed.

I have referred to the valves s and t as "expansion-valves," because they operate to cut off steam at different points of the stroke of the piston.

Supposing the engine to be started with the crank in the position shown in Fig. 2, when the crank is in this position, the exhaust-valve e is closed and the expansion-valve s and intermediate valve 9 are open. Boiler-steam will then flow from passage 6^a in valve-chest k and port 6 to passage 5 in leg of stationary abutment f , as shown in dotted lines in Fig. 2, through the abutment-head into the piston-cylinder d and through the latter into cylinder c . Owing to the greater cross-sectional area of the inner face of the piston-head of cylinder d relatively to the like area

- of the outer face of said head the piston will make or complete its outstroke, the crank and fly-wheel revolving in the direction of arrow, Fig. 2. As the piston-cylinder *d* completes or is about to complete its outstroke, Fig. 5, the exhaust-valve *e* will open to exhaust the steam from the engine, the intermediate valve *g* and the expansion-valve *s* will close, while the expansion-valve *t* opens, Fig. 7, to admit steam through passage *6*¹ in valve-chest *k*, port *6*, passage *5* in leg of stationary abutment *f*, through the head thereof to piston-cylinder *d*, causing the latter to make its instroke. As said piston-cylinder *d* completes or is about to complete its instroke the expansion-valve *t* and exhaust-valve *e* close, while the intermediate valve *g* and expansion-valve *s* open, so that the steam in piston-cylinder *d* is exhausted into cylinder *c*, instead of being exhausted into the atmosphere, as is now the case, while at the same time boiler-steam is admitted through passage *6*², port *6*, passage *5* in leg of abutment *f*, as shown in dotted lines in Fig. 4, through head of said abutment into the piston-cylinder *d*, and through the latter cylinder into cylinder *c*, causing the exhaust-steam from cylinder *d* and the boiler-steam to act expansively in a measure to effect the outstroke, the engine working semicom pound, the described operations being repeated.
- Inasmuch as the steam required to effect the instroke of the piston-cylinder *d* instead of being wasted is utilized in conjunction with boiler-steam on the outstroke the engine is operated more economically than would be the case otherwise.
- It will be obvious to any engineer that the described engine will work without the expansion-valves *s* and *t*, but not as economically as with them, the valves *e* and *g* being the main valves that control the operation of the engine, the valves *s* and *t* controlling the steam distribution the same as in the well-known Corliss engine, with the same economical advantages.
- In practice the best results are obtained by providing a differential cut-off for the two cylinders--such, for instance, as that when the governor *x* causes the valve *t* for the piston-cylinder to cut-off at or about half-stroke the valve *s* for the stationary cylinder will cut-off at or about quarter-stroke.
- I am aware that compound engines comprising a stationary low-pressure cylinder, a stationary abutment, and a high-pressure cylinder reciprocating on said abutment and within the low-pressure cylinder are well known, and I do not therefore desire to lay claim, broadly, to such an arrangement.
- Having thus described my invention, what I claim as new therein, and desire to secure by Letters Patent, is—
1. In a double-acting high-pressure steam-engine, the combination with a stationary cylinder, a stationary abutment and a power-cylinder reciprocating in said stationary cylinder and on said abutment; of means operating automatically to admit boiler-steam to the power-cylinder to effect the instroke, to exhaust the steam in said power-cylinder into the stationary cylinder and simultaneously admit boiler-steam to the last-named cylinder to effect the outstroke, for the purposes set forth.
  2. In a double-acting high-pressure steam-engine, the combination with a stationary cylinder, a stationary abutment, and a piston-cylinder reciprocating in said stationary cylinder and on said abutment; of means operating automatically to admit boiler-steam to the piston-cylinder to effect the instroke and to the stationary cylinder to effect the outstroke, for the purposes set forth.
  3. In a double-acting high-pressure steam-engine, the combination with a stationary cylinder, a stationary abutment, and a piston-cylinder reciprocating in said stationary cylinder and on said abutment; of means for automatically admitting boiler-steam to the piston-cylinder to effect the instroke and to the stationary cylinder through said piston-cylinder to effect the outstroke, for the purposes set forth.
  4. In a double-acting high-pressure steam-engine, the combination with a stationary cylinder, a stationary abutment and a piston-cylinder reciprocating in said stationary cylinder and on said stationary abutment; of means operating automatically to admit boiler-steam through said abutment to the piston-cylinder to effect the instroke and to the stationary cylinder to effect the outstroke, for the purposes set forth.
  5. In a double-acting high-pressure steam-engine, the combination with a stationary cylinder, a stationary abutment and a piston-cylinder reciprocating in said stationary cylinder and on said abutment; of means operating automatically to admit boiler-steam through said abutment to the piston-cylinder to effect the instroke, and through said piston-cylinder to the stationary cylinder to effect the outstroke, for the purposes set forth.
  6. In a double-acting high-pressure steam-engine, the combination with a stationary cylinder, a stationary abutment and a piston-cylinder reciprocating in said stationary cylinder and on said abutment; of means operating automatically to admit boiler-steam to the piston-cylinder to effect the instroke, to exhaust the steam in said piston-cylinder into the stationary cylinder and simultaneously admit boiler-steam to the last-named cylinder to effect the outstroke, for the purpose set forth.
  7. In a double-acting high-pressure steam-engine, the combination with a stationary cylinder, a stationary abutment and a piston-cylinder reciprocating in said stationary cylinder and on said abutment; of means operating automatically to admit boiler-steam to the piston-cylinder to effect the instroke, to exhaust the steam in said piston-cylinder into

the stationary cylinder and simultaneously admit boiler-steam to the last-named cylinder through the piston-cylinder to effect the out-stroke, for the purposes set forth.

5 8. In a double-acting high-pressure steam-engine, the combination with a stationary cylinder, a bifurcated stationary abutment having a steam-passage through one of its legs and its head, and a piston-cylinder reciprocating in said stationary cylinder and on said abutment; of a valve-chest in direct communication with the inlet of the steam-passage in the abutment-leg, and two alternately-operating main valves in said chest, 15 and means operating automatically to admit boiler-steam from the abutment to the piston and stationary cylinders alternately, for the purposes set forth.

9. A semicompound engine comprising a stationary cylinder, a stationary abutment, a piston-cylinder having motion on said abutment and in said stationary cylinder, an exhaust-valve, means for admitting boiler-steam to both cylinders, valves controlling the admission of steam thereto, and means for operating said valves, for the purposes set forth.

10. A semicompound engine comprising a stationary cylinder, a stationary abutment, a piston-cylinder having motion on said abutment and in said stationary cylinder, an exhaust-valve, means for admitting boiler-steam to both cylinders, valves controlling the admission of steam thereto, and independently-

timed appliances for operating said valves, for the purposes set forth. 35

11. A semicompound engine comprising a stationary cylinder, a stationary abutment, a piston-cylinder having motion on said abutment and in said stationary cylinder, an intermediate valve controlling ports in the head 40 of the piston-cylinder an exhaust-valve for the stationary cylinder, means for admitting boiler-steam to said piston-cylinder to effect the instroke, and two valves controlling said admission, and independently-timed appliances for operating said admission-valves and the exhaust and intermediate valves to admit boiler-steam to the stationary cylinder to effect the outstroke, for the purposes set forth. 45

12. The combination with a stationary cylinder, a stationary abutment, and a piston-cylinder working on said abutment and in said stationary cylinder; of a valve controlling the flow of steam from the piston-cylinder to the stationary cylinder, the stem of said valve extending through the piston-head of the piston-cylinder toward the crank-shaft, for the purposes set forth. 50

In testimony that I claim the foregoing as my invention I have signed my name in presence of two subscribing witnesses.

MARCY L. WHITFIELD.
